APPLYING MACHINE

Harold C. Coppins, Buffalo, N. Y., assignor to
 F. N. Burt Company, Limited, Toronto, Ontario, Canada, a corporation of Ontario, Canada

Application December 16, 1932, Serial No. 647,565

52 Claims. (Cl. 93—55.1)

This invention relates to an improved applying machine, the features of which are capable of use in numerous different associations, but which are primarily intended for employment in connection 5 with the manufacture of receptacles such as paper boxes and their parts.

By means of the present invention an apparatus is provided which will embody relatively few parts, each individually simple and rugged in 10 construction and capable of assemblage to furnish a machine operating for long periods of time with freedom from difficulty and the necessity of manual supervision.

It is another object of the invention to provide 15 a machine of the character described embodying improved mechanism capable of operation at relatively high speeds, and which will operate in an improved and efficient manner to prevent clogging of the machine or the forming of imperfect receptacle parts in any case where the receptacle forming material is not properly supplied.

A further and more particular object of the invention is to provide, in a machine of the class mentioned, an improved mechanism operating 20 with efficiency and rapidity for applying and adhesively attaching layers of material, such as finishing strips, to the surfaces of boxes or receptacle parts.

Other objects of the invention will be in part 25 pointed out in the following detailed description of an illustrative but preferred embodiment of the invention, and will be in part obvious in connection therewith.

The invention accordingly comprises the features of construction, combinations of elements and arrangement of parts which will be exemplified in the construction hereinafter described, and the scope of the application of which will be indicated in the claims.

For a full and complete disclosure of the nature 30 and objects of the invention, and of the improved mechanism according to the illustrative embodiment of the invention, reference is had to the following detailed description, and to the accompanying drawings, in which:

Fig. 1 is a fragmentary side elevation of an apparatus embodying the invention, parts being in section and parts omitted so as to show more clearly important features of the improvements;

Fig. 2 is an end elevation of the apparatus shown in Fig. 1;

Fig. 3 is a fragmentary elevation of the delivery mechanism for delivering articles, such as box parts, at the receiving station of the machine;

Fig. 4 is an enlarged elevation of the turret for applying the finishing strips, parts being broken away and in section;

Fig. 5 is an enlarged fragmentary sectional and elevational view of the turret for carrying the 5 receptacle or box parts;

Fig. 6 (Sheet 1) is a sectional view taken substantially on the line 6—6 of Fig. 4, looking in the direction indicated by the arrows;

Fig. 7 (Sheet 1) is a section taken substantially 10 on the line 7—7 of Fig. 4, looking in the direction indicated by the arrows;

Fig. 8 (Sheet 5) is a face view of the fluid control valve disk which is normally assembled with 15 the turret shown in Fig. 5;

Fig. 9 is a longitudinal section and elevation of the mechanism for transferring articles, such as receptacle parts, to the initial station of the machine;

Fig. 10 is a longitudinal sectional and elevational view of the mechanism for applying the 20 strip;

Figs. 11 to 17 inclusive are detail views of different operating mechanisms for various elements of the machine, and

Fig. 18 (Sheet 2) is a face view of a control disk or plate shown in assembled position in Fig. 4.

For a detailed description of the illustrative but preferred embodiment of the invention, reference is first made to Figs. 1 and 2, showing the deck 30 20, supporting the two principal units of the machine including turrets 21 and 22. The turret 21 receives and retains the box or receptacle part to one end of which a blank or finishing strip, herein shown in the form of a disk of paper, is 35 applied through the cooperation of the turret 22.

As shown in Fig. 3, the receptacle parts are in the form of cylindrical box bodies, as indicated in dot and dash outline, these being moved to the machine along a downwardly inclined runway including a base or supporting plate 23 to which upright side strips 24 or guides are adjustably attached by bolts 25 riding within slots 26 of the brackets 27 secured by clamps 28 to the base plate. 40 By means of this structure, the height of the sides or guide rails 24 may be easily varied, and the width of the chute may also be readily varied by a lateral adjustment of the clamps 28.

Some types of receptacle or box parts handled 50 by this machine have flange or side wall portions which are quite fragile and considerable care must be exercised in order to avoid damage to these parts. Therefore, the receptacle of this type, which is about to be introduced into the 55

- machine should be somewhat segregated from the following receptacles. Of course, where flange portions or their equivalents do not form parts of the receptacles, it is usually unnecessary to 5 utilize a segregating mechanism. As will be noted in Fig. 3, this mechanism may include a rocker arm 29 adjustably carried by a bracket 30, and at the ends of this arm, springs or spring fingers 31 are secured so that the receptacles or other 10 material being handled by the machine may be engaged to allow the lowermost receptacle in the chute to move downwardly, while holding the remaining receptacles in spaced relation thereto. The rocker arm may be guided by a crank arm 32 15 secured to a link 33, with which the spring 34 is coupled. The spring serves normally to urge the outermost contact finger downwardly, but the link may be reciprocated to swing the parts to the other extreme position by any suitable operating 20 means connected to the link, such as an arm 35 secured to a shaft 36. The mechanism for oscillating this shaft will be hereinafter described. Adjacent the lower end of the chute the side walls thereof may terminate. In line with points 25 beyond the same are a series of angularly spaced, radially adjustable guides 37, the outermost of which have foot portions 38 which act to prevent the receptacle from moving along the chute beyond a predetermined point.
- In line with the center, as defined by the radially extending guide and stop members 37, is the axis of a unit which transfers the receptacle parts or other material from the chute to the 30 turret 21. This transfer unit, as shown especially in Fig. 9, may include a cylinder 39 within which a piston 40 reciprocates. Movements of this piston beyond a predetermined point are prevented by an adjustable stop 41 and secured to the piston is a rod 42 which extends through 35 a stuffing box 43 and terminates in a head 44 of an area such that it may pass through the space defined by the inner ends 38 of the guides 37. The head 44 may carry a guide or stop 45 which extends towards the chute and supplements the 40 action of the segregating mechanism if the latter is employed. In other words, as the head is projected, this guide rides against the side edge of that unit of material which is next to be fed to the machine and prevents the same from moving to a position at which it might become injured. Reciprocation of the piston and head is effected by coupling the ends of the cylinder through tubes 46 with a source of fluid pressure.
- As clearly shown in Fig. 1, the transfer unit 45 or plunger 44 is disposed beyond the inclined article or box body chute while the turret 21 is disposed at the opposite side of the chute and in line with the transfer head 44. The turret 21 includes a central hub portion 47 from which 50 angularly spaced supporting arms 48 extend outwardly, carrying outwardly disposed article supporting heads or mandrels 49. As best shown in Fig. 5, each of these supporting heads includes a cup-shaped box supporting member 50 having grooves 51 in its outer face and being attached to 55 its supporting arm 48 by a bolt 52 having an aperture or conduit extending therethrough and communicating with openings 53 leading to the grooves 51.
- When a receptacle or other unit of material 60 moves down the runway and assumes a position in line with the space defined by the inner ends of the guides 37 and thereupon the head 44 is projected to push this unit of material towards the head 49, it will be obvious that the unit will be

mounted thereon and be retained thereby, especially if the bore of the bolt 52 is connected with a source of vacuum. Conversely if fluid under pressure flows through the bore of the bolt, the unit will be ejected from the head. In order that fluid may pass through the bore of the bolt in the manner described, it will be seen that the arm 48 is formed with a bore 54, with which the hollow bolt communicates. Each bore 54 is continued in the form of a branch extending to the side face of the hub element 47 of which the arms 48 form a part. Overlying this side face is a rotatable disk 55 which, as shown in Fig. 8 has a series of grooves or ports in its side face. As shown, these grooves are in the form of arcs of a common circle and are identified by the reference numerals 56, 57, 58 and 59. The first and third of these are connected by tubes 60 with a source of suction (not shown). The channel 59 is connected with a source of fluid pressure (not shown) by means of a tube 61. A tube 62 extends from the channel or groove 57 and the purpose of this latter tube will be hereinafter brought out.

As best shown in Fig. 4 the turret 22 includes a body or hub 63 from which arms 64 extend. Adjacent the outer ends of the arms, collars 65 are provided, these collars slidably mounting rods 66 which are normally urged upwardly by means of encircling springs 67. At their lower ends the rods carry heads 68 which embrace perforated face plates 69. The hub 63 slidably supports a rod 70 carrying arms 71 having their ends positioned for alignment with the upper ends of rods 66. Adjustable contact members 72 are mounted by both of the arms 71 and it will be obvious that if the rod 70 is retracted with reference to the hub 63, these contact members would come to bear against the upper faces of the rods 66, thereby depressing the heads 68 against the resistance of the springs 67. The hub 63 terminates in a base portion 73 housing one or more downwardly extending springs 74 which bear against the upper face of a plate 75, best shown in Fig. 18. The plate in turn rests upon a base 76 and a member providing a side wall 77 is secured to the base 73 and overlaps plate 75 and the upper edge of the base 76, it being noted that this member is formed with a circumferential series of perforations 78, which are normally in line with the side edge of the plate 75. The faces of the base portions 73 and 76 are best shown in Figs. 6 and 7 respectively, wherein it will be noted that the base 73 is formed with ports 79, and with a series of recesses which accommodate the springs 74. Connected to the ports are tubes 80 which extend one to each of the heads 68. The ports 79 open into an annular groove 81 formed in the face of the base, it being noted that each port is framed by a downwardly extending flange member 82 extending into the groove 81 and terminating in the same plane as the lower surface of the base 73. The plate 75 has openings 83 in line with the ports 79 and bolts (not shown) extend through further openings 84 of this plate into openings 85 formed in the upper base 73. Thus the plate 75 is mounted to rotate with the upper base, but the bolts are so adjusted that the plate will rest upon the base portion 76 and that the base 73 may move towards and away from the plate 75, it being of course obvious that, with the plate intimately in contact with the lower face of the base 73, fluid will flow directly through the openings 83 and the ports 79, while if the plate is spaced from the

base, the ports 79 will be interconnected through the groove 81.

The base or hub 76, as shown in Fig. 7, is formed with a groove 86, which extends through slightly more than a semi-circle. The groove is in constant communication with at least one of the openings 83 and, by means of a tube 87 is connected preferably to the same source of suction (not shown) as that to which the tube 60 of turret 21 is connected. A tube 88 is also connected to the groove 86 and this tube is either identical with, or else connected to the tube 62 shown in Fig. 8, thus communicating through the conduits 54 (Fig. 5) with the heads 49.

The base or hub portion 76 is mounted for rotary oscillation upon a standard 89 and has a pin 90 which is connected to an actuator 91, best shown in Fig. 11. This actuator takes the form of a fork at the outer end of a rocker arm, which latter is link-connected, as at 92, to a crank 93 connected by a link 94 to a follower 95 cooperating with a cam 96. The cam is mounted by a shaft 97 which is driven in a manner hereinafter brought out, and it will be observed that this shaft carries a cam 98 cooperating with a follower 99 link-connected as at 100 to a lever 101. The lever is pivotally mounted and normally has its outer end urged downwardly by a spring 102. Adjacent this outer end the lever 101 may have notched portions which cooperate with the centering extensions 102, which may be V-shaped in cross section.

Accordingly, with the shaft 97 rotating, the lower base section or hub 76 will be periodically oscillated, while the arm 101 will cooperate with the edge portions of the extensions 102 in order that the arms 64 and heads 68 carried thereby may be accurately and periodically aligned with the operating contact elements 72.

As has been previously brought out, the turret 22 is to receive material and apply the same to the receptacle part carried by the turret 21. Preferably, the material supplied to the turret 22 comes from a magazine (see Fig. 2), having vertically extending guide members 103, defining between them a space sufficient for the accommodation of a stack of blanks 104. This magazine is disposed in line with rest positions of the heads 68 of the turret 22 and a base 105 forms a part of the magazine and serves to elevate the stack of blanks so that the uppermost may cooperate with the turret head. This elevation is achieved preferably by employing a screw-threaded rod 106 which passes through a similarly threaded nut 107, and which nut is rotated by employing a pawl and ratchet mechanism 108. The nut 107 is preferably of the more or less conventional type which is split and capable of being opened by actuation of a handle 109 so that the shaft 106 may be manually elevated or depressed.

In moving from the magazine station to the station at which the blank is delivered to the receptacle part carried upon one of the heads 49, the head 68 passes a glue roller 110, best shown in Fig. 1. This adhesive applying roller may take any desired form and include, for example, a plurality of annular ribs, and is rotated by means of a sprocket gear 111 and partially immersed within a glue tank 112. Thus, if a blank is carried by the head 68 and the latter is in depressed position, it is obvious that the lower face of the blank will come in contact with and be coated by the glue roller.

When the blank is adhesively treated as de-

scribed, the head 68 continues its rotary movement in its relatively depressed position until it comes into alignment with the mandrel or head 49 at Station B. At this point the operating arm 71 descends (see Fig. 4), thus moving the carrying head 68 downwardly and causing the adhesively treated blank to be pressed into contact with the surface of the box blank or part supported upon the mandrel 49. In this manner the blank or strip is adhesively attached to the box part whereupon the suction grip of the head 68 upon the blank will be released and said head will be retracted and its rotary movement continued at the next operative cycle.

In certain instances, it is desirable that the blank transfer at this initial applying station should be supplemented by an action whereby the blank is forced into intimate contact with the surface to which it is applied. Thus as shown in Fig. 1, a fluid cylinder 112' serves to reciprocate a pressing pad 113 to engage the outer face of the blank and to yieldingly press the same into engagement with the box or other article on the head 49. As best shown in Fig. 10, the cylinder 112' may be divided into sections by a central wall 114 and within each of these sections pistons 115 reciprocate in directions controlled by the flow of fluid through tubes 116. The pistons 115 are coupled by a rod 117 which carries at its outer end the pad 113 and it is thus obvious that the desired pressure may be transmitted to the outer face of the blank.

When cylindrical boxes are being handled and blanks, such as finishing strips or labels, are to be applied to the box parts, a supply of such parts is delivered into the inclined chute shown in Fig. 3. Also as shown in Fig. 2 a supply of blanks 104 is disposed in the supply magazine. The motor 118, through a reduction gearing 119 and a clutch 120, serves to drive a shaft 121 which, by means of gears 122 rotates the cam shaft 97. By means of a Geneva movement 123, best illustrated in Fig. 12, an intermediate rotation is imparted to the shaft 124 to which turret 21 is operatively connected. Also coupled to this shaft is a bevel gear 125 which meshes with a gear 126 coupled with a sleeve or tube 127 connected to the hub 63, as shown in Fig. 4. The ratio of gears 125 and 126 is 1 to 2 so that for each revolution of the shaft 124 the sleeve 127 is turned through two complete revolutions. As shown in Figs. 2 and 12, the shaft 121 carries a gear 128 meshing with a gear 129 on a shaft 130 carrying a sprocket 131 meshing with a sprocket chain 132 which is connected to the sprocket 111 of the adhesive roller 110 shown in Fig. 1. Therefore, by the mechanism described both turrets 21 and 22 are intermittently rotated through operation of the Geneva stop movement, and the periods of rest resulting from this drive occur when one of the mandrel heads 49 of the turret 21 is adjacent to the plunger head 44 of the box transfer device. The next advance head of the turret 21 extends vertically under the head 68 of turret 22; the third head of turret 21 extending during this period in line with the head or pad 113, and the fourth head extending downwardly in line with a discharge opening 133 adjacent which a chute 133' may be disposed. Obviously, during these periods of rest the two heads 68 overlie the uppermost head 59 of the turret 21 and the blank supply magazine, respectively. Referring to Fig. 1, it will now be apparent that the mandrel heads 49 of the turret 21 and the box parts thereon will be subjected simultaneously to the following

operating steps: first: a box part will be supplied from the inclined chute through operation of the transfer plunger 44 at station A to one of the mandrel heads 49 then positioned in alignment with said plunger; second: at station B a disk or finishing strip will be applied by operation of the suction head 68 to the receptacle part on the head 49 at this station; third: at station C the applied finishing strip will be pressed into contact with the end of the receptacle part by operation of the plate or head 113; fourth: the completed receptacle part will be expelled at station D from the mandrel head into the chute 133' provided therefor. Since all of the different operating steps mentioned are simultaneously performed after each successive shift of the turret 21, it will, therefore, be seen that a box part is completed at each such shift.

Obviously, the head 49 adjacent station A, is in communication through its bore 54 with port 56 so that the receptacle delivered to it will be drawn into intimate contact with the head portions. Immediately thereafter port 57 communicates with the branch and bore connected to this head, the purpose of this construction being also hereinafter brought out. As the head reaches station B, at which the disk is applied, its branch and communicating bore 54 are connected to groove or port 58 so that from this point on, and through and beyond station C, the material carried by the head is continuously subjected to the action of suction to insure against its being displaced from said head. Adjacent the fourth or discharge station D the port 59 communicates with the bore 54 and its branch and air under pressure will now flow to the head to expel the completed article. It will be understood that the plate 55 is shifted by mechanism hereinafter described so that the vacuum and pressure effects will occur with sufficient force.

As shown in Figs. 4, 6, 7 and 14, it will be noted that the rod 70 and arm 71 of the turret 72 reciprocate and rotate with respect to the hub 63 and head portions 68 associated therewith. This result is achieved by means of a lever 134 coupled to the lower end of the rod 70 and which has a second arm connected to a rod 135 and spring 136. Rod 135 is coupled to a follower 137, as shown in Fig. 14, and this follower rides against the surfaces of a cam 138 with which it is pressed into contact by the spring 136. Obviously therefore, as the shaft 97 rotates, the cam will cause the rod 70 to be periodically elevated and lowered, and this will in no wise interfere with the rotation of the hub 63 and its associated parts. The cam is so timed that the arms 71 lower when the heads 68 are located respectively under these arms and in line respectively with the magazine carrying blanks 104 and the uppermost head 49 of turret 21 at station A. Such lowering will cause each rod 66 to be depressed against the action of its spring 67, resulting in the lower face of one plate 69 being pressed into contact with the uppermost finishing strip or disk in the magazine, while the lower face of the second head plate 69 is moved towards the upper surface of the receptacle carried by that head 49 which occupies station B. This downward movement of the heads 68 will obviously place the springs 74 under compression and move the base 73 into contact with the plate 75, said springs being sufficiently weak as compared with the springs 67 to accomplish this result. With the tube 87 connected to a source of vacuum supply and the perforations of the plate 69 of both heads sealed

by disks, it is apparent that the suction will act through the groove 86, openings or ports 83 and ports 79 to transmit the suction so as to retain the disks in intimate association with the underfaces of the plate 69, and to retain the plate 75 in intimate contact with the base 73, due to the fact that the openings 78 in the annular sealing plate 77 will be sealed. This, of course, is conceding that air may not enter through tube 88. Such entry of air is precluded if a receptacle has been received by the head 49 adjacent station A of turret 21 so as to close the grooves 51 and openings 53 and consequently when the channel or port 57 is connected to the bore 54, no air flow will occur through the latter nor through the tube 62, nor, consequently, the tube 88. Therefore, the base 73 will remain immediately adjacent the plate 75, with the springs 74 under compression. If, however, no receptacle has been applied to the head 49 at station A, it is obvious that air will be free to flow through the bore 54 and so through tube 62 and tube 88, as a consequence of which the vacuum through port 79 and tube 80 will be broken. When this occurs it is patent that the base 73 will rise under the influence of springs 74 and the initial position of the parts may not be re-established, because the perforations 78 will now be uncovered, thus sufficiently breaking the suction to prevent this occurring. If, as will be normally the case, receptacles seal the bores 54 of the heads 49, then of course the base 73 will remain lowered and consequently as the arm 64 swings the head 68 past the glue roller, the underface of the disk carried by the head will come in contact with such roller and be guided thereby. However, if no receptacle is present and the hub 63, together with its associated parts is elevated, the underface of the plate 69 will clear the roller and the disk will remain uncoated.

In each instance, after the hub 73 has been elevated, it will be apparent that under normal operation, the machine will endeavor to re-establish the proper cycle of operation, due to the fact that the rod 70 will reciprocate, thus pressing the head 68 downwardly and compressing the springs 74 incident to greater resistive force offered by the springs 67. Again, however, if no receptacle is present upon the next head 49 of the turret 21, the springs 74 will again re-establish the inoperative condition of the parts. Consequently, any disk or blank picked up by the heads 68 will simply remain uncoated and be loosely deposited upon the head 49 occupying station B. Thereupon, and as turret 21 rotates, this disk will drop clear. Through operation of the mechanism shown in Fig. 11 the proper positioning of the heads 68 is at all times assured, as is also the shifting of the control base or disk 76. In connection with the latter it will be understood that as in Fig. 7, the groove 86 extends preferably in excess of 180°. This permits of suction acting on both heads 68 as they are depressed incident to the retraction of the rod 70. Consequently the one blank or disk is retained while suction tends to draw the uppermost disk in the magazine into contact with the second head. At that moment, the disk 76 shifts so that suction to the first head is interrupted and the adhesively treated disk associated therewith will be retained in contact with the receptacle applied to the uppermost head 49 of the turret 21. The pawl and ratchet mechanism 108 for feeding the blanks 104 in the magazine (see Fig. 2) may be actuated, as shown in Fig. 15, by a rod 139.

which is normally spring-projected, as at 140, and is capable of retraction by means of bell-crank levers and links 141 in turn coupled to a follower 142 cooperating with cam 143 secured to shaft 97.

Referring to the remaining controls illustrated, it will be observed, as in Fig. 13, that a cam 144 may be secured to the shaft 97 and cooperate with a follower 146 which is coupled to the shaft 10 140 in order to reciprocate link 33. Referring next to Fig. 14, it is to be observed that the gear 122 carries on its outer face a cam shoe 147 which cooperates with a valve control 148 in order to connect a cylinder 149 to a source of fluid under 15 pressure. Extending from this cylinder is a rod 150 which is connected or forms a part of rod 135. Consequently, bellcrank lever 134 is shifted in one direction by the cam 138 but rocks in the opposite direction by virtue of the spring 136 as 20 well as under the action of fluid pressure.

As shown in Fig. 16, the toothed gear 122 carries a cam element 151 with which a follower 152 cooperates. This follower is normally spring-retracted as at 153 and is link-connected as at 25 154 to a valve 155. This valve controls the flow of fluid from a source of pressure (not shown) through tube 61 as described in connection with Fig. 8.

Finally, referring to Fig. 17, it will be noted 30 that the shaft 97 additionally carries a cam 156 cooperating with a follower 157 which is spring-pressed, as at 158, and is connected by link 159 to a valve 160. This valve is connected by a tube 161 to the source of fluid under pressure and extending from such valve are the tubes 46 and 116 controlling the cylinders shown in Figs. 9 35 and 10, respectively.

From the foregoing it will be understood that 40 a machine is provided which is capable of use in numerous different associations, but which is of primary utility when employed in the manufacture of receptacles. In such association it will serve effectively to handle receptacle portions and to apply thereto end disks. If for any 45 reason a receptacle part is not applied at Station A upon the mandrel head of the turret 21 the vacuum at the suction head 68 positioned at the magazine carrying the blanks 104 (see Fig. 2) will be broken, and consequently one of the blanks 50 or finishing strips will not be picked from the magazine as the head 68 rises upon retraction of the operating arm 71. At the same time, the vacuum in the channel or chamber 81 (see Fig. 4) will be broken and the turret 22 together with the 55 heads 68 will be moved upwardly slightly due to the expanding action of the springs 74, thus positioning the head 68 moving past the adhesive roll 110, so that said head does not contact with the roll. In this manner, application of the adhesive to the surface of the plate 69 of the head 68 is avoided entirely eliminating smearing or 60 continuation of the parts.

Since certain changes may be made in the 65 above construction and different embodiments of the invention could be made without departing from the scope thereof, it is intended that all matter contained in the above description or shown in the accompanying drawings shall be interpreted as illustrative and not in a limiting 70 sense.

Having described my invention, what I claim as new and desire to secure by Letters Patent is:

1. In an applying machine, a turret head having a hollow portion, a base portion, a supporting

member, means tending to maintain such base portion spaced from said supporting member, said head being perforated, means connecting the hollow portion of said head with the space existing between said base portion and supporting member and means connecting said base portion with a source of vacuum, whereby when an article is applied to the perforations of said head, said base portion and supporting member will be drawn into intimate association. 10

2. In an applying machine, a turret head having a hollow portion, a base portion, a supporting member, means tending to maintain such base portion spaced from said supporting member, said head being perforated, means connecting the hollow portion of said head with the space existing between said base portion and supporting member, means connecting said base portion with a source of vacuum, whereby when an article is applied to the perforations of said head, said base portion and supporting member will be drawn into intimate association thus depressing said head, means for moving said head and means disposed in the path of travel of said depressed head to render adhesive the material carried thereby. 20

3. In an applying machine, a turret head having a hollow portion, a base portion, a supporting member, means tending to maintain such base portion spaced from said supporting member, said head being perforated, means connecting the hollow portion of said head with the space existing between said base portion and supporting member, means connecting said base portion with a source of vacuum, whereby when an article is applied to the perforations of said head, said base portion and supporting member will be drawn into intimate association and means acting upon such vacuum being broken, to maintain said base portion and supporting member substantially out of contact with each other. 30

4. In an applying machine, a turret head having a hollow portion, a base portion, a supporting member, means tending to maintain such base portion spaced from said supporting member, said head being perforated, means connecting the hollow portion of said head with the space existing between said base portion and supporting member, means connecting said base portion with a source of vacuum, whereby when an article is applied to the perforations of said head, said base portion and supporting member will be drawn into intimate association, thus depressing said head, means for moving said head, means disposed in the path of travel of said depressed head to render adhesive the material carried thereby, a second turret head having a hollow perforated body to which material is to be applied and means connecting said second head to said 50 first named head to break the suction in the event of material being not applied to said second head. 55

5. An applying machine including a pair of turrets, means for delivering material to both of 60 said turrets, means disposed adjacent one of said turrets to treat the material carried thereby, means for movably supporting such turret whereby the material associated therewith may operatively engage said last mentioned means, 70 means acting in the absence of material in association with the second turret to shift said first mentioned turret to a position at which said material will not operatively engage said treating means and means tending to reshift such 75 turrets.

- ret to operative position with respect to said treating means.
6. An applying machine including a source of article supply, a head, a support, a slideway for slidably mounting said head with respect to said support, a spring holding said head away from said source in retracted position in said slideway, means for shifting said head to overlie said source and means for projecting said head against the resistance of said spring towards said source of article supply.
7. An applying machine including a projectible turret, a head carried by said turret, means for shifting articles to said head, means for maintaining such articles in association with said head, means for shifting said turret, means disposed in the path of travel of said head and during such shifting to treat an article associated with said head, and means acting in the absence of an article to project said turret, whereby said head will have a path of travel beyond said treating means.
8. An applying machine including a projectible turret, a head carried by said turret, means for shifting articles to said head, means for maintaining such articles in association with said head, means for shifting said turret, means disposed in the path of travel of said head and during such shifting to treat an article associated with said head, means acting in the absence of an article to project said turret, whereby said head will have a path of travel beyond said treating means and means for periodically retracting said head.
9. An applying machine including a projectible turret, a head carried by said turret, means for shifting articles to said head, means for maintaining such articles in association with said head, means for shifting said turret, means disposed in the path of travel of said head and during such shifting to treat an article associated with said head, means acting in the absence of an article to project said turret, whereby said head will have a path of travel beyond said treating means, means for periodically retracting said head and means responsive to the presence of an article in association with said head for maintaining the latter and said turret in retracted position.
10. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, and pneumatic means for pneumatically holding said elements in said operative relative positions.
11. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions and means controlled by articles on said supporting element to release said pneumatic holding means in the absence of an article on said supporting element.
12. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions in which said treating element becomes operative for treating an article on said supporting element, pneumatic means for pneumatically holding said elements in said operative relative positions in which said treating element becomes operative to position said elements out of their said operative relative positions.
13. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions, means controlled by articles on said supporting element to release said pneumatic holding means in the absence of an article on said supporting element, and means thereupon becoming operative to position said elements out of their said operative relative positions.
14. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions, means controlled by articles on said supporting element to release said pneumatic holding means in the absence of an article on said supporting element, and intermittently operating means to re-establish said pneumatic holding means in holding condition.
15. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions, means controlled by articles on said supporting element to release said pneumatic holding means in the absence of an article on said supporting element, means thereupon becoming operative to position said elements out of their said operative relative positions and intermittently operating means to position said elements again in their said operative relative positions and to re-establish said pneumatic holding means in holding condition.
16. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions, a second article supporting element, and means for adhesively attaching the articles carried by said first and second supporting elements.
17. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions.

relative positions, a second article supporting element, means for adhesively attaching the articles carried by said first and second supporting elements and means controlled by articles on either of said supporting elements to release said pneumatic holding means in the absence of an article on either of said supporting elements.

17. In a machine of the character described, in combination, an article supporting element, a treating element for rendering adhesive an article carried by said supporting element, means for mounting said supporting and treating elements for relative movement into and out of relative positions in which said treating element becomes operative for treating an article on said supporting element, pneumatic means for pneumatically holding said elements in said operative relative positions, a second article supporting element, means for adhesively attaching the articles carried by said first and second supporting elements, means controlled by articles on either of said supporting elements to release said pneumatic holding means in the absence of an article on either of said supporting elements and means thereupon becoming operative to position said elements out of their said operative relative positions so as to prevent adhesive treatment of said first mentioned article supporting element.

18. In a machine of the character described, in combination, an article supporting element, a treating element for rendering adhesive an article carried by said supporting element, means for mounting said supporting and treating elements for relative movements into and out of relative positions in which said treating element becomes operative for treating an article on said supporting element, pneumatic means for pneumatically holding said elements in said operative relative positions, means for moving said article supporting element with a step by step movement and means for periodically projecting said supporting element from its normal position to deposit an article carried thereby.

19. In a machine of the character described, in combination, an article supporting element, a treating element for rendering adhesive an article carried by said supporting element, a rotary supporting turret for said supporting element mounted for axial movement, and means for moving said turret axially upon failure of an article on the supporting element so as to avoid a treating operation by said treating element.

20. In a machine of the character described, in combination, an article supporting element, a treating element for rendering adhesive an article carried by said supporting element, a rotary supporting turret for said supporting element mounted for axial movement, and a pneumatic holding device controlled by articles on said supporting element for pneumatically holding said turret in its axial position wherein said supporting element is in position for treating co-operation with said treating element upon turret rotation.

21. In a machine of the character described, in combination, an article supporting element, a treating element for rendering adhesive an article carried by said supporting element, a rotary supporting turret for said supporting element mounted for axial movement, a pneumatic holding device controlled by articles on said supporting element for pneumatically holding said turret in its axial position wherein said supporting element is in position for treating co-operation with said treating element upon turret rotation, means for releasing said pneumatic holding means in the

absence of an article on said supporting element, and means for thereupon moving said turret axially so as to avoid a treating operation by said treating element.

22. In a machine of the character described, in combination, a pair of rotary turrets having their axes of rotation angularly disposed to each other, means for rotating said turrets in unison, blank supporting heads carried by said turrets, means for transferring a blank carried by one head and applying it to a blank on a head of the other turret, a treating element for rendering adhesive a blank carried by one of said heads and being mounted adjacent to the path of movement of the latter, and automatic means for moving the turret carrying said last mentioned head to position the latter out of cooperative relation with said treating element.

23. In a machine of the character described, in combination, an article supporting element, a treating element for rendering adhesive an article carried by said supporting element, a rotary turret carrying said supporting element for movement in a path to position the carried article in contact with said treating element, means for mounting said turret for movement into position so that the path of the carried article is spaced from said treating element, and pneumatically controlled means for moving said turret so that the carried article travels in said last mentioned path.

24. In a machine of the character described, in combination, an article supporting element, a treating element for rendering adhesive an article carried by said supporting element, a rotary turret carrying said supporting element for movement in a path to position the carried article in contact with said treating element, means for mounting said turret for movement into position so that the path of the carried article is spaced from said treating element, a plate connected to said turret, means normally urging said turret into said last mentioned position, and means for establishing a vacuum adjacent to said plate to hold the turret so that the carried article travels in said first mentioned path.

25. In a machine of the character described, in combination, an article supporting element, a treating element for rendering adhesive an article carried by said supporting element, a rotary turret carrying said supporting element for movement in a path to position the carried article in contact with said treating element, means for mounting said turret for movement into position so that the path of the carried article is spaced from said treating element, a plate connected to said turret, means normally urging said turret into said last mentioned position, means for establishing a vacuum adjacent to said plate to hold the turret so that the carried article travels in said first mentioned path, and automatically controlled means for breaking said vacuum whereby said urging means becomes operative to position said supporting element in said second mentioned path.

26. In a machine of the character described, in combination, an article supporting element, a treating element for rendering adhesive an article carried by said supporting element, a rotary turret carrying said supporting element for movement in a path to position the carried article in contact with said treating element, means for mounting said turret for movement into position so that the path of the carried article is spaced from said treating element, a plate connected to

said turret, means normally urging said turret into said last mentioned position, means for establishing a vacuum adjacent to said plate to hold the turret so that the carried article travels in said first mentioned path, automatically controlled means for breaking said vacuum whereby said urging means becomes operative to position said supporting element in said second mentioned path, means for preventing re-establishment of the vacuum from moving said turret into its original position, and further means for moving said turret into its original position.

27. In a machine of the character described, in combination, a blank supporting head, a second blank supporting head, means for relatively moving said heads into adjacent transfer relation with reference to each other, means including a pneumatic device whereby said first head is caused to pneumatically pick up blanks successively and to successively apply them to blanks on the second head, and means to prevent picking up of a blank by said first head in the absence of a blank on said second head.

28. In a machine of the character described, in combination, a plurality of blank supporting heads, means including a pneumatic blank holding device whereby blanks are successively picked up by one of said heads and successively applied to blanks on another head, and means operative under predetermined conditions to control said pneumatic device whereby picking up of blanks by said one head is interrupted.

29. In a machine of the character described, in combination, a plurality of blank supporting heads, means including a pneumatic blank holding device whereby blanks are successively picked up by one of said heads and successively applied to blanks on a second of said heads, and means controlled by absence of a blank on said second head to control said pneumatic device to interrupt the picking up of blanks by said one head.

30. In a machine of the character described, in combination, a plurality of blank supporting heads, means whereby blanks are successively picked up by one of said heads and successively applied to blanks on a second of said heads, said picking means including pneumatic blank holding means for holding blanks on said one head whereby the latter is enabled to pick up and hold the blanks, and means for controlling said pneumatic means by absence of a blank on said second head to interrupt the picking up of blanks by said one head.

31. In a machine of the character described, in combination, two blank supporting heads, means whereby blanks are successively picked up by one of said heads and successively applied to blanks on the other head, said picking means including pneumatic blank holding means for holding blanks on each of said heads and to enable said one head to pick up the blanks, and means whereby said pneumatic means is in simultaneous communication with both heads so as to cause interruption to the picking up of blanks by said one head in the absence of a blank on said other head.

32. In a machine of the character described, in combination, two blank supports, means whereby blanks are successively picked up by one of said supports and successively applied to blanks on the other support, pneumatic blank holding means for holding blanks on each of said supports and to enable said one support to pick up the blanks, a rotary turret supporting said one support and being mounted for bodily movement

from normal operative position thereof, and pneumatic holding means normally holding said turret from bodily movement and being in communication with said pneumatic blank holding means.

33. In a machine of the character described, in combination, two blank supports, means whereby blanks are successively picked up by one of said supports and successively applied to blanks on the other support, pneumatic blank holding means for holding blanks on each of said supports and to enable said one support to pick up the blanks, a rotary turret supporting said one support and being mounted for bodily movement from normal operative position thereof, pneumatic holding means normally holding said turret from bodily movement and being in communication with said pneumatic blank holding means, and means whereby said pneumatic holding means are in simultaneous communication with both supports so as to release the turret to bodily movement and to cause interruption to the picking up of blanks by said one support in the absence of a blank on said other support.

34. In a machine of the character described, in combination, two blank supports, means whereby blanks are successively picked up by one of said supports and successively applied to blanks on the other support, pneumatic blank holding means for holding blanks on each of said supports and to enable said one support to pick up the blanks, a rotary turret supporting said one support and being mounted for bodily movement from normal operative position thereof, pneumatic holding means normally holding said turret from bodily movement and being in communication with said pneumatic blank holding means, means whereby said pneumatic holding means are in simultaneous communication with both supports so as to release the turret to bodily movement and to cause interruption to the picking up of blanks by said one support in the absence of a blank on said other support, means for thereupon effecting bodily movement of said turret, and means for rendering adhesive a blank carried by said one support and positioned for cooperation with the latter at the normal position thereof, but to be out of cooperating position upon said bodily movement of the turret.

35. In a machine of the character described, in combination, a blank support, a rotary turret carrying a blank supporting head in an endless path, means whereby blanks are successively picked up by said supporting head and successively applied to blanks on said support, means operative under predetermined conditions whereby picking up of blanks by said head is interrupted, and means for rendering one of the blanks adhesive prior to application of one blank to the other.

36. In a machine of the character described, in combination, a blank support, a rotary turret carrying a blank supporting head in an endless path, means whereby blanks are successively picked up by said supporting head and successively applied to blanks on said support, means operative under predetermined conditions whereby picking up of blanks by said head is interrupted, means for rendering one of the blanks adhesive prior to application of one blank to the other, and means for rendering said adhesive means ineffective in the absence of a blank on said head.

37. In a machine of the character described, in combination, a blank support, a rotary turret

carrying a blank supporting head in an endless path, means whereby blanks are successively picked up by said head and successively applied to blanks on said support, means controlled by absence of a blank on said support to interrupt the picking up of blanks by said head, means for rendering one of the blanks adhesive prior to application of one blank to the other, and means for rendering said adhesive means ineffective in the absence of a blank on said support.

38. In a machine of the character described, in combination, two blank supporting heads, means whereby blanks are successively picked up by one of said heads and successively applied to blanks on the other head, pneumatic blank holding means for holding blanks on both of said heads and to enable said one head to pick up the blanks, means whereby said pneumatic means is in simultaneous communication with both heads so as to cause interruption to the picking up of blanks by said one head in the absence of a blank on said other head, means for rendering one of the blanks adhesive prior to application of one blank to the other, and means for rendering said adhesive means ineffective in the absence of a blank on one of said heads.

39. In a machine of the character described, in combination, two blank supporting heads, means whereby blanks are successively picked up by one of said heads and successively applied to blanks on the other head, pneumatic blank holding means for holding blanks on both of said heads and to enable said one head to pick up the blanks, a rotary turret supporting said one head and being mounted for bodily movement from normal operative position thereof, pneumatic holding means normally holding said turret from bodily movement and being in communication with said pneumatic blank holding means, and adhesive applying means positioned for cooperation with said one head only before bodily movement of said turret from its normal position.

40. In a machine of the character described, in combination, a rotary turret carrying a plurality of article supporting heads, means for adhesively applying blanks to articles on said heads, a support for articles, a rocker arm mounted adjacent to said support, and having article contacting fingers positioned at opposite sides of the axis of the arm and spaced apart a distance substantially equal to the width of the articles, means for rocking said arm to bring the fingers alternately into contact with the articles to deliver them one by one and to check advancement of the adjacent following articles, and a transfer plunger positioned adjacent to said arm and mounted for movement transversely of the path of the articles delivered from said fingers for laterally transferring the articles to the heads of the turret.

41. In an article delivery device, in combination, a support for articles, a rocker arm mounted adjacent to said support, and having article contacting fingers positioned at opposite sides of the axis of the arm and spaced apart a distance substantially equal to the width of the articles, means for rocking said arm to bring the fingers alternately into contact with the articles to deliver them one by one and to check advancement of the adjacent following articles, a transfer plunger positioned adjacent to said arm and mounted for movement transversely of the path of the articles delivered from said fingers for laterally transferring the articles, and an article stop

carried by said plunger and positioned to check articles when the plunger is advanced.

42. In an article delivery device, in combination, an inclined article runway, means adjacent the runway for feeding the articles one by one therefrom, a plurality of article positioning guides positioned radially with reference to a point opposite to the later mentioned transfer plunger, said guides being supported for adjustment longitudinally of their radial positions for positioning the articles emerging from said feeding means and a transfer plunger for transferring the articles laterally of their path from the runway.

43. In a machine of the character described, in combination, a source of article supply, an article supporting head, a rotary support for said head, means including a supporting stem for slidably mounting said head in said support for movement transversely of the plane of rotation of the latter, and an operating member mounted for reciprocating transversely of the plane of rotation of said rotary support and contacting intermittently with said stem to project the head into contact with said source of supply.

44. In a machine of the character described, in combination, a source of article supply, an article supporting head, a rotary support for said head, means including a supporting stem for slidably mounting said head in said support for movement transversely of the plane of rotation of the latter, a reciprocating rod concentric with the axis of rotation of said head, and an operating member carried by said rod and reciprocating with the latter transversely of the plane of rotation of the rotary support and contacting intermittently with said stem to project said head into contact with said source of supply.

45. In a machine of the character described, in combination, a source of article supply, two oppositely disposed article supporting heads, a rotary support for said heads, means for rotating said support with a step by step movement so as to stop one of said heads adjacent to said source and to stop the other head at the same time opposite to a second article, mounting means supporting each of said heads on said rotary support for movement transversely of the plane of rotation of the rotary support, and an actuator for transversely moving said heads on their mounting means to cause one head to contact with an article at said source and to cause the other head to contact with said second article.

46. In a machine of the character described, in combination, a source of article supply, two oppositely disposed article supporting heads, a rotary support for said heads, means for rotating said support with a step by step movement so as to stop one of said heads adjacent to said source and to stop the other head at the same time opposite to a second article, mounting means supporting each of said heads on said rotary support for movement transversely of the plane of rotation of the rotary support, and a reciprocating actuator movable transversely to the plane of rotation of said rotary support and cooperating intermittently for transversely moving said heads on their mounting means to cause one head to contact with an article at said source and to cause the other head to contact with said second article.

47. In a machine of the character described, in combination, an article supporting element, a treating element for rendering adhesive an article carried by said supporting element, a rotary supporting turret for said supporting element,

means for mounting said rotary turret for movement of translation to and from cooperative relation of said article supporting element with said treating element, and means controlled through 5 the agency of articles to cause said turret to be positioned for cooperation of the supporting element with the treating element when an article is positioned upon said supporting element, and to cause it to be translated to non-cooperative 10 position in the absence of an article on the supporting element.

48. In a machine of the character described, in combination, a blank support, blank supporting means, means for effecting engagement of 15 said supporting means and blanks of a supply source with each other, means for holding an engaged blank to said supporting means, means to operate said blank supporting means to pick blanks held thereby from said source and to 20 transfer them for application to blanks on said blank support, and automatically controlled means operative under certain conditions for rendering said blank holding means ineffective 25 to hold a blank on said supporting means and thus to prevent picking of a blank from the supply source.

49. In a machine of the character described, in combination, a blank support, blank supporting means, means for effecting engagement of 30 said supporting means and blanks of a supply source with each other, means for holding an engaged blank to said supporting means, means to operate said blank supporting means to pick blanks held thereby from said source and to 35 transfer them for application to blanks on said blank support and automatic blank controlled means operative in the absence of a blank on said blank support for rendering said holding means

ineffective to hold a blank on said supporting means and thus to prevent picking of a blank from the supply source.

50. In a machine of the character described, in combination, a blank support, blank supporting means, means for effecting engagement of said supporting means and blanks of a supply source with each other, means for holding an engaged blank to said supporting means, means to operate said blank supporting means to pick 10 blanks held thereby from said source and to transfer them for application to blanks on said blank support, means for adhesively treating a blank on said supporting means, and automatic blank controlled means operative in the absence 15 of a blank on said blank support for rendering said treating means ineffective and for rendering said holding means ineffective to hold a blank on said supporting means so as to prevent picking of a blank from the supply source. 20

51. In a machine of the character described, in combination, a rotary turret, a blank carrying head carried by said turret, means for shifting said turret bodily out of its normal operative position, means normally retaining said turret in 25 its normal operative position, and automatic means for releasing said retaining means.

52. In a machine of the character described, in combination, a rotary turret, a blank carrying head carried by said turret, means for shifting 30 said turret bodily out of its normal operative position, means normally retaining said turret in its normal operative position, automatic means for releasing said retaining means, and intermittent means for restoring said turret to its normal 35 operative position after having been shifted therefrom.

HAROLD C. COPPINS.
